BOTTLE

Arnold I. Lorenzen, deceased, late of Toledo, Ohio, by Gertrude M. Lorenzen, executrix, Toledo, Ohio, as signor to Owens-Illinois, Inc., Toledo, Ohio, a corporation of Ohio

Filed May 20, 1965, Ser. No. 85,411

Term of patent 14 years

(Cl. D58—6)

FIG. 1

The back and side not shown are the same as the

The dominant features of the design reside in the portion

What is claimed is:

The ornamental design for a bottle, substantially as shown and described.
